Corporation, Syracuse, N. Y., a corporation of
Delaware

Application March 16, 1945, Serial No. 583,022

7 Claims. (Cl. 62—115)

1

This invention relates to refrigeration and more particularly to the art of obtaining and/or maintaining relatively low temperatures by the utilization of a single refrigeration stage, and in which the refrigeration effect so obtained and/or maintained may be carried through any desired number of stages to maintain or to decrease the relatively low temperatures first obtained.

Prior to the instant invention, relatively low temperatures have been obtained by the utilization of more than one refrigeration stage. For example, in some prior systems, the condenser of a compressor-condenser-expander system, utilizing carbon dioxide as a refrigerant, has been cooled by the evaporator of a compressor-condenser-expander system utilizing ammonia as a refrigerant. While the example referred to employs the compression type of refrigeration system, the disadvantages inherent in such systems apply equally to absorption systems. These prior systems are expensive and complicated because of the use of a great many elements including the use of two compressors and in some cases the use substantially of two entire refrigeration systems.

It is an object of the instant invention to provide a refrigeration system which will be simple and relatively inexpensive to manufacture and economical to operate for the production of relatively low temperatures.

It is another object of the instant invention to employ a novel combination of elements served by a single stage of refrigeration for obtaining low temperatures.

It is another object of the instant invention to employ a novel combination of elements served by a single stage of refrigeration for obtaining low temperatures in which the temperatures so obtained may be maintained or decreased through any desired number of stages.

Other objects and the nature and advantages of the invention will be apparent from the following description to be read in conjunction with the accompanying drawings, wherein:

Figure 1 is a schematic view of a refrigeration system in accordance with the invention; and

Figure 2 is a view similar to Figure 1 of a modified form of the invention.

Referring to Figure 1, the compressor 10 serves to compress the refrigerant and discharge it through conduit 11 into condenser 12 from which it is passed in liquid form through feed line 13 into the conduit 14, through the expansion valve

15, when valve 16 is closed, and then through the coil 17 located within the brine bath 18 in insulated chamber 19. The refrigerant passes from the coil 17 into the conduit 20 when the valve 21 is open, then through coil 23 and back through the suction line 24 into compressor 10 to complete the cycle. The expansion valve 15 is controlled by the bulb T in contact with the suction line 24 at the discharge end of coil 23.

10 It will be understood, if desired, bulb T may be disposed at the exit of coil 17 instead of the position chosen.

With the valve 16 closed as described, the coil 17 acts as an evaporator and cools the brine 18 within insulated chamber 19. The temperature of the brine 18 will be lowered to a level much cooler than ordinary condenser coolants such as the outside air, or cooling water obtained from a well or municipal system. After the temperature 15 of the brine bath 18 has reached a desired low level, the valve 16 may be opened and valve 21 closed. Expansion valve 22 will now function under control of bulb T' in the usual manner. Valves 16 and 21 may be operated manually or 20 automatically as desired. The expansion valves 15 and 22 function automatically, of course, by 25 means of the bulb controls T and T'.

The arrangement, upon cooling of the brine to a desired temperature, is in condition to operate 30 as a low temperature refrigeration system. The hot gaseous refrigerant is conducted along feed line 13 and passes through valve 16 into coil 17 where it is condensed and possesses a much lower temperature than it had when leaving condenser 12 which, in this stage, is ineffective for condensation. The brine 18 permits a much lower condensing temperature and pressure so that condensation occurs in coil 17. Thus, when 35 the condensed refrigerant passes through the expansion valve 22 to the coil 23, which now acts as an evaporator, refrigerating temperatures will be obtained therein much lower than those produced when conventional condenser cooling means are alone employed.

40 With the system arranged as described, utilizing coil 17 at one time, as during normally idle periods, as an evaporator to cool brine 18, and at another time as a condenser for gaseous refrigerant, such cooled refrigerant when evaporated in a second coil, 23, effectively produces relatively 45 low temperatures; and this is accomplished with a simple apparatus requiring a minimum of elements.

50 It is to be understood that though coils 17 and

23 are shown connected in series, they may be arranged in a series-parallel relationship with the use of appropriate valves, so that when coil 17 is used as an evaporator to cool brine 18, coil 23 may be completely by-passed, and the gas from coil 17 proceeds directly to the compressor. Then, when coil 17 is used as a condenser for cooling the refrigerant passing therethrough (that is, giving off heat to the already cooled brine 18), it will be in series with coil 23 which then acts as an 10 evaporator.

Also, if it is desired to employ coils 17 and 23 in series, the refrigerant after cooling the brine, may be used in coil 23 for cooling air or gases flowing across coil 23, but the temperature of coil 23 in such event will be higher than when the brine is used for condensing the refrigerant and coil 23 used as the primary evaporator.

The duration of the low temperature effect may be of any desired length dependent upon the quantity of brine stored in chamber 19 and hence the duration of the storage cycle.

It will be understood the system described above is not limited to the stages of refrigeration described since additional stages may be obtained by adding additional coils and brine tanks. In other words, a suitable series of brine tanks may be arranged to pass the refrigeration effect from one to the other until a desired low temperature is reached and/or maintained.

The system described in connection with Figure 1 serves to operate the evaporator 23 at relatively low temperatures intermittently since time periods are required for cooling the brine at which times coil 23 does not function as a low temperature evaporator. When it is desired to utilize this system in such a manner as to make available relatively low temperature conditions at desired intervals, a system may be used corresponding to that shown in Figure 2.

In Figure 2, compressor 110 discharges refrigerant gas through line 111 whence it passes through condenser 112. The liquefied refrigerant then passes through feed line 113, into line 114, and through expansion valve 115, valve 116 being closed; then through the coil 117 located within brine bath 118 in insulated chamber 119. The refrigerant leaving coil 117 then passes through the line 120, the valve 121 being open and expansion valve 122 closed; through the coil 123 within the area to be conditioned 125, and back to compressor 110 through suction line 124 to complete the cycle. Area 125 is the one which requires a relatively low temperature.

So far the system is the same as in Fig. 1 and may be operated in the same way. However, provision is here made for supplying the cold brine 118 from chamber 119 through line 126 into coil 127 within an area to be conditioned 128. A pump P circulates the brine from chamber 119 to coil 127 and back to chamber 119 through return line 129. Thermostat or equivalent control T located within the brine 118 controls valves 115, 116, 122, and 121 in such a manner that when the temperature of the brine 118 goes above a predetermined level, the expansion valve 115 will be opened, the valve 116 closed, expansion valve 122 closed and the valve 121 opened so that the coil 117 will become an evaporator to cool the brine to a temperature below a predetermined fixed point. Thus, the temperature of the brine coil 127 within area 128 will be constantly below a predetermined fixed point and substantially constant cooling will be obtained within area 128.

When it is desired to obtain comparatively lower temperatures in area 125, then expansion valve 115 will be closed, valve 116 opened, expansion valve 122 opened and valve 121 closed so that coil 123 will become a primary evaporator. It will be understood that suitable fans or blowers may be provided for circulating air or gases over coils 123 and 127. When coil 123 is used as the primary evaporator, pump P may be shut down. While this will cut off refrigeration service in area 128, it will enable lower temperatures to be obtained in coil 123. Thus the system may be employed with maximum effect in a restaurant, for example, where light loads between meal hours are encountered in the restaurant proper (area 128), during which time freezer space (area 125) may effectively be served.

Valves 115, 116, 121 and 122 may be manually controlled if desired, and automatic controls of different types will suggest themselves to those skilled in the art for cutting in and out of service responsive to changing load conditions or prescribed settings.

Applicant therefore provides a simple yet effective arrangement for providing low temperatures while utilizing compressor and evaporator elements no larger than those heretofore considered incapable of providing equivalent low temperature performance.

Since various changes may be made without departing from the spirit of the invention, no limitations are intended with respect to the systems shown in the drawings and described in the specification but only as indicated in the appended claims.

I claim:

1. A refrigeration system for obtaining relatively low temperatures comprising a compressor, a condenser, a first coil, and a second coil, said compressor, condenser and two coils being connected in a closed circuit; a first expansion valve in said circuit associated with the inlet of said first coil; a second expansion valve associated with the inlet of said second coil; a first by-pass conduit connected in said circuit for by-passing said first expansion valve; means for shutting off and opening said first by-pass conduit; a second by-pass conduit connected in said circuit for by-passing said second expansion valve; second means for shutting off and opening said second by-pass conduit; and a thermal hold-over disposed in heat exchange relation with said first coil; said circuit being so arranged that when said first expansion valve is in operation, and the first by-pass conduit is closed by said means, said second expansion valve does not function, and the second by-pass conduit is open whereby said first coil acts as an evaporator to pre-cool said thermal hold-over; said circuit being further arranged so that when said first by-pass conduit is open and the first expansion valve does not function, said second expansion valve is in operation and the second by-pass conduit is closed by said second means whereby the refrigerant in said first coil will be condensed subsequent to its leaving the compressor and said second coil will act as a relatively low temperature evaporator to produce relatively low temperatures in the ambient atmosphere about said second coil.

2. The structure recited in claim 1, said first coil and said second coil being connected in series.

3. The structure recited in claim 1, said thermal hold-over comprising a brine tank within which said first coil is located.

4. A refrigeration system for obtaining rela-

tively low temperatures comprising a compressor, a condenser, a combined heat absorbing and heat rejecting element, a cold holdover, a low temperature evaporator, means for first utilizing said combined heat absorbing and heat rejecting element as an evaporator for removing heat from said cold holdover, and then, as a heat rejector after a desired temperature is obtained in said cold holdover, to reject heat to said cold holdover for condensing the refrigerant therewithin prior to its passage to the low temperature evaporator, whereby relatively low ambient temperatures will be obtained about said low temperature evaporator, said means including a line connecting the condenser with said element, expansion means in said line, a by-pass line about the expansion means, a valve for closing and opening the by-pass, a third line connecting said element and the low temperature evaporator, second expansion means in the third line, a second by-pass line about the second expansion means, and a second valve for closing and opening the second by-pass.

5. A refrigeration system for obtaining certain low temperatures intermittently, and other low temperatures substantially constantly, comprising a compressor, a condenser, a combined heat absorbing and rejection element, a brine tank arranged about said heat absorbing and heat rejecting element, a relatively low temperature evaporator, means for first utilizing said combined heat absorbing and heat rejecting element as an evaporator to remove heat from said brine tank and then as a heat rejector after a desired temperature is obtained in said cold holdover to transfer heat to said brine tank for condensing the refrigerant therewithin prior to its passage to the relatively low temperature evaporator whereby relatively low ambient temperatures will be maintained about said relatively low temperature evaporator said means including a line connecting the condenser with said element, expansion means in said line, a by-pass line about the expansion means, a valve for closing and opening the by-pass, a third line connecting said element and the low temperature evaporator, second expansion means in the third line, a second by-pass line about the second expansion means and a second valve for closing and opening the second by-pass, a cooling element connected in thermal association with said brine tank, means for circulating brine through said cooling element and means for maintaining said cooling element below a predetermined temperature level.

6. In a refrigeration system for obtaining relatively low temperatures, the combination of a compressor, a condenser for volatile refrigerant,

- a first coil, a brine chamber in which said first coil is disposed, a second coil, said compressor, condenser and coils being connected in a closed circuit; an expansion valve disposed in said circuit associated with the inlet to said first coil, a by-pass conduit connected in said circuit for by-passing said expansion valve, first means for opening and closing said by-pass conduit; a second expansion valve disposed in said circuit associated with the inlet to said second coil, a second by-pass conduit connected in said circuit for by-passing said second expansion valve, and second means for opening and closing said second by-pass conduit; said circuit being so arranged that when the first expansion valve is in operation and the first by-pass conduit is closed by said first means, said second expansion valve does not function and the second by-pass conduit is open whereby said first coil serves as an evaporator to pre-cool the brine in said brine chamber; said circuit being further arranged to provide that when said first by-pass conduit is open and the first expansion valve does not function, said second expansion valve is in operation and the second by-pass conduit is closed by said second means, whereby the refrigerant in said first coil will be condensed and said second coil will act as a relatively low temperature evaporator to produce relatively low temperatures in the ambient atmosphere about said second coil.

7. The method of obtaining relatively low temperatures comprising compressing a volatile refrigerant, condensing said volatile refrigerant, expanding the volatile refrigerant to refrigerate a precooling medium, then after said precooling medium has attained a desired temperature utilizing said precooling medium to condense volatile refrigerant, evaporating the refrigerant condensed by said precooling medium to obtain a relatively low temperature in air circulated in heat exchange relation therewith, and utilizing said precooling medium to cool a space at a relatively higher temperature level.
